UNITED STATES PATENT OFFICE.

ALFRED C. CLAS, OF MILWAUKEE, WISCONSIN, ASSIGNOR TO THE
MILWAUKEE CARNIVAL ASSOCIATION, OF SAME PLACE.

DESIGN FOR A BADGE OR SIMILAR ARTICLE.

SPECIFICATION forming part of Design No. 28,625, dated May 17, 1898.

Application filed February 8, 1898. Serial No. 669,596. Term of patent 3½ years.

To all whom it may concern:

Be it known that I, ALFRED C. CLAS, a citizen of the United States, residing at Milwaukee, in the county of Milwaukee and State of Wisconsin, have invented and produced a new and original Design for Badges or Similar Decorative Devices; and I do hereby declare the following to be a full, clear, and exact description of the same, reference being had to the accompanying drawing, forming a part thereof.

The said drawing is a plan view illustrating my said design.

My design relates particularly to the new and original surface ornamentation of the decorative device or display.

The leading feature of this design comprises

a representation of a hoop having bells suspended therefrom, said hoop having a filling of fabric, after the manner of circus-hoops, and showing a head thrust therethrough, tearing said fabric, the head wearing a fool's cap and being emblematical of folly.

Having described my invention, what I claim as new, and desire to secure by Letters Patent, is—

The design for a badge or similar article, substantially as herein shown and described.

In testimony whereof I affix my signature in presence of two witnesses.

ALFRED C. CLAS.

Witnesses:

H. G. UNDERWOOD,
LULU RUSCHA.
